UNITED STATES PATENT OFFICE

2,285,307

LAMP SHADE CONSTRUCTION

Samuel Sher, Chicago, Ill.

Application December 9, 1939, Serial No. 308,403

2 Claims. (Cl. 240—108)

This invention relates to lamp shade construction, and particularly to novel means for securing the covering material of the shade to the frame thereof.

One object of the present invention is to provide novel means for securing the covering material to a lamp shade frame without the use of stitching or the like.

Another object of the invention is to provide means on the frame itself whereby the covering material may be readily and conveniently secured thereto.

A further object of the invention is to provide a simple, inexpensive and efficient arrangement to facilitate the securing of the covering material to a lamp shade frame in a minimum amount of time.

A still further object of the invention is to improve devices of the character described in sundry details hereinafter referred to and particularly pointed out in the appended claims.

One embodiment of the present invention is shown for illustrative purposes in the accompanying drawing in which:

Fig. 1 is an elevational view of a lamp shade structure embodying features of the present invention, portions of the shade structure being broken away to better illustrate the construction thereof;

Fig. 2 is an enlarged sectional elevational view of the structure illustrated in Fig. 1, and taken substantially as indicated by the line 2—2 thereof;

Fig. 3 is an enlarged fragmentary side elevational view of a portion of the structure illustrated in Figs. 1 and 2;

Fig. 4 is a fragmentary plan view on an intermediate scale of a portion of the structure illustrated in Figs. 1 to 3, inclusive;

Fig. 5 is a fragmentary perspective view of a portion of the structure forming a part of the present invention; and

Fig. 6 is an enlarged fragmentary sectional elevational view similar to a portion of Fig. 2, illustrating a slightly different manner of applying the covering material to the frame structure.

In the drawing, the present invention is illustrated as applied to a lamp shade construction shown, in the present instance, as comprising a frame having an upper frame member indicated, as a whole, by the numeral 11 and a lower frame member 12 connected together and spaced apart by means shown, in the present instance, as a plurality of rods 13 positioned at intervals around the shade structure, the shade when fin-

ished including a covering material indicated, as a whole, by the numeral 14, and formed, preferably, of an elongated strip of suitable fabric or the like, adapted to surround the frame members 11 and 12 and the rods 13, the upper portion of the shade being finished off with a strip of braid 15, or other suitable trim, as illustrated in Fig. 1.

The upper frame member 11 is shown, in the present instance, as comprising a substantially flat strip 16 formed preferably of suitable flexible metal, adapted to be bent into the form desired and shown, in the present instance, as of annular or circular construction, and secured to the strip 16, preferably on the outer side thereof, is a relatively thinner flexible strip 17 adapted to conform to the curvature or shape of the strip 16 and to be secured thereto by spot welding, for example, or other suitable means.

For conveniently securing the covering material 14 to the frame, the upper frame member is provided with a plurality of hooks shown, in the present instance, as struck-up portions formed on the strip 17 and indicated, as a whole, by the numeral 18, the struck-up portions 18 being adapted to be forced outwardly from the vertical plane of the strip 17 and having a portion 19 extending substantially parallel to the outer face of the strip and in spaced relation thereto.

The portion 19, as shown in the present instance, is provided, preferably, with an arrow or spear-head like portion 21 having a pointed end 22 adapted to readily pierce the covering material 14 and is provided, in the present instance, with a plurality of oppositely disposed, preferably inclined shoulders 23 facing in the opposite direction to the pointed end 22, thereby providing a structure for retaining the cover material 14 against accidental displacement after being positioned over the arrow-head like portion 21, as clearly illustrated in Fig. 3.

As illustrated in Fig. 2, the covering material 14 may be applied to the frame by slipping the edge portion 24 of the covering material 14 over the arrow-head like portion 21 and drawing the material snugly over the upper frame member 11 and downwardly on the inner side of the frame, thence snugly around the lower frame member 12 and upwardly on the outer side of the frame to the upper portion thereof, where the edge portion 25 of the covering material 14 is pierced by the point 22 and the material forced over the arrow-head like portion 21 and drawn upwardly in a manner to rest on or be engaged by the shoulders 23 for retaining the covering material in proper relation and secured to the frame por-

tion of the shade structure, as illustrated in Figs. 2 and 3, after which, and for concealing the edge portion 25 of the covering material and the struck-up portions 18 of the frame member, a trim 15 of braid or other suitable material may be placed around the frame member 11, as illustrated in Fig. 1.

In Fig. 6 is shown a slightly different manner of applying the covering material to the frame, wherein the upper edge portion 25a of the covering material 14 is first applied to the struck-up portions 18 and carried downwardly on the outer side of the frame and around the lower frame member thereof, thence upwardly on the inner side of the frame and having its opposite edge portion 24a pierced by the point 22 and drawn upwardly over the shoulders 23, thereby forcing the edge portion 25a upwardly along the struck-up portion 18 to the position shown in Fig. 6, thus securing the covering material 14 to the frame in a manner similar to that illustrated in Fig. 2, except that the covering material is applied to and wrapped around the frame in the opposite direction.

It will be observed from the foregoing description that the present invention provides a novel and convenient construction and arrangement whereby the covering material may be readily applied and secured to the frame of a shade structure in a minimum amount of time and without the use of stitching or the like.

Obviously, the present invention is not limited

to the precise construction and arrangement shown and described as the same may be variously modified without departing from the spirit and scope of the invention as set forth in the appended claims.

What I claim as new and desire to secure by Letters Patent is:

1. In a lamp shade, the combination of a frame comprising a pair of vertically spaced upper and lower connected frame members, a plurality of pointed hooks formed on one side of one of said members and spaced laterally from the adjacent face thereof, each of said hooks having a plurality of shoulders extending laterally therefrom and facing in the opposite direction to the pointed ends of said hooks, and a covering of flexible material surrounding said frame members, one edge portion of said covering engaging said hooks and the opposite edge portion of the covering being in engagement with the shoulders on said hooks.

2. In a lamp shade, the combination of a frame comprising a pair of vertically spaced upper and lower connected frame members, a plurality of circumferentially spaced, pointed, arrow-head like hooks formed on the outer side of one of said members and spaced laterally from the adjacent outer face thereof, and an elongated strip of flexible material surrounding said frame members and having its opposite longitudinal edge portions engaging said hooks.

SAMUEL SHER.
